CLAIM

The ornamental design for a pharmaceutical storage tray, as shown and described.

DESCRIPTION

FIG. 1 is a top plan view of the pharmaceutical storage tray, showing the new design.

FIG. 2 is a bottom plan view thereof.

FIG. 3 is a front elevation view thereof.

FIG. 4 is a back elevation view thereof.

FIG. 5 is a right side elevation view thereof.

FIG. 6 is a left side elevation view thereof; and,

FIG. 7 is a perspective view of the pharmaceutical storage tray.

The portions of the disclosure in FIG. 7 shown in broken lines are for illustrative purposes only and form no part of the claimed design.
